UNITED STATES PATENT OFFICE.

ABE R. SPIELBERGER, OF ATLANTA, GEORGIA.

FOUNTAIN COMB AND CARTRIDGE THEREFOR.

1,407,230.

Specification of Letters Patent. Patented Feb. 21, 1922.

Application filed May 23, 1921. Serial No. 471,714.

To all whom it may concern:

Be it known that I, ABE R. SPIELBERGER, a citizen of the United States, residing at Atlanta, in the county of Fulton and State of Georgia, have invented certain new and useful Improvements in Fountain Combs and Cartridges Therefor; and I do declare the following to be a full, clear, and exact description of the invention, such as will enable others skilled in the art to which it appertains to make and use the same.

This invention relates to an improved construction in a fountain comb and cartridge therefor and one object of the invention is to provide a fountain comb having an improved handle construction in which a cartridge containing a hair preparation may be placed and to provide an improved breech carried by the handle and having mechanism for engaging a threaded stem mounted in the cartridge and for turning the stem to move a piston longitudinally of the cartridge to force the contents of the cartridge out of the cartridge and into a passage formed in the head of the comb and communicating with passages formed in certain of the comb teeth.

Another object of the invention is to so construct the breech that it may be securely but releasably held in a closed position and to so mount the mechanism within the breech that the cartridge will be tightly forced into place when the breech is closed.

Another object of the invention is to so construct this mechanism within the breech that the cartridge will be retained in place and a turning key slidably and rotatably mounted in the breech held in engagement with the head of the turning screw of the cartridge.

Another object of the invention is to provide an improved ratchet mechanism for preventing the key of the breech from being turned in a reverse direction and further serving as signal means to indicate the extent the key has been rotated.

Another object of the invention is to provide an improved heat insulating connection and shield between the hollow handle and head of the comb so that the head may be heated and the heat prevented from

passing to the handle and also the operator's hand protected from the heat of the head.

Another object of the invention is to so construct the head and handle that a very tight joint will be provided and to further provide means for forming a tight joint between the cartridge and inner end of the head thus preventing leakage of material when forced out of the cartridge.

Another object of the invention is to so construct this head that it may be very easily cleaned by removing a plug closing the outer end of the passage through the head and forcing hot water or some other cleaning fluid through the passage.

This invention is illustrated in the accompanying drawings, wherein:

Figure 1 is a view showing the fountain comb in side elevation.

Figure 2 is a top plan view of the improved comb.

Figure 3 is an end elevation looking at the breech end of the comb.

Figure 4 is a view showing the comb in longitudinal section.

Figure 5 is a transverse sectional view taken along the line 5-5 of Fig. 4.

Figure 6 is a sectional view taken along the line 6-6 of Fig. 4.

Figure 7 is a view taken along the line 7-7 of Fig. 4.

Figure 8 is a view of the ratchet disk mounted in the breech.

Figure 9 is a view of the pawl disk carried by the key within the breech for engaging the ratchet disk, and controlling rotation of the key.

Figure 10 is a view showing the cartridge in side elevation.

Figure 11 is an end elevation of the cartridge.

Figure 12 is a side elevation showing a modified form of breech.

Figure 13 is an end elevation of the breech shown in Figure 12.

Figure 14 is a sectional view taken along the line 14-14 of Figure 12.

Figure 15 is a perspective view of the bridge used in the modified form of breech.

This improved fountain comb is provided with a hollow handle 1 in the form of a tube

which fits upon the enlarged end portion 2 of the comb head 3, a bushing 4 of asbestos or other heat insulating material being provided within the handle or tube 1 about the 5 enlarged end 2 of the head and secured in place by the securing screws 5 which pass through the tube and bushing and are screwed into threaded sockets formed in the enlarged end of the comb head. The outer 10 end portion of this bushing is formed into an outstanding collar or shield 4' to protect the operator's hand from injury by the heat of the comb head. A packing disk 6 is provided in this tube or hollow handle 1 for fitting 15 against the inner end of the enlarged end 2 of the comb head and is provided with a central opening 7 for registering with the enlarged end portion or cup 8 provided within the enlarged end of the comb head 20 at the end of the passage 9 which extends longitudinally through the comb head. This passage 9 has its outer end closed by a removable threaded plug 10 and is provided with side passages 11 which pass through 25 certain of the teeth 12 of the comb.

The cartridge 13 which carries the hair ointment or oil fits within the handle 1 and in cross-section conforms to the shape of the handle. In the present illustration, the 30 handle and the cartridge are oval in cross-section, but it is to be understood that they may be round or any other shape desired. This cartridge is provided with heads 14 and 15 at its ends, the head 14 having an 35 opening formed therein to receive a threaded stem or rod 16 which extends through a washer 17 and carries a disk 18 which prevents the threaded stem from moving outwardly. The outer end portion of the stem 40 is provided with a turning head and in the form illustrated is split longitudinally and bent to provide a head having arms 19 which will engage the washer 17 and thus be prevented from scraping against the head 14 45 when turned. A piston 20 is positioned in the body of the cartridge and in threaded engagement with the rod or stem 16 so that when this stem is rotated, the piston will be moved toward the head 15 and the ointment 50 or oil in the cartridge forced through the outlet or neck 21 into the cup 8 and through the passage 9 into the passages 11 of the teeth. When not in place, the cartridge will be provided with a suitable closure 22 which 55 is removable so that it can be taken off when the cartridge is placed in the comb handle. It should be noted that the cartridge is slightly longer than the tubular handle thus making it easy to remove the cartridge and 60 further that the threaded stem does not extend the full length of the cartridge. Therefore, when the device is in use, and the stem turned, the piston 20 will finally be moved into close engagement with the head 65 15 and out of threaded engagement with the

stem. The stem will then turn freely and indicate that the cartridge is empty and further by means of this construction, danger of breakage will be prevented as no resistance will be offered which might tend to cause breakage of the threads of the stem or portions of the breech mechanism.

The breech is in the form of a cup or cap 23 which fits upon the end of the tubular handle 1 and is preferably hingedly mounted as shown at 24. A resilient or spring latching strip 25 is secured to the handle and extends longitudinally thereof for passing through a seat formed on the side of the cap by ribs 26. This spring strip 25 is provided at its free end with a head 27 for fitting into a notch 28 formed in the side of the cap at the end of the seat formed by the ribs 26. It will thus be seen that the cap can be easily swung to the closed position and in doing so, the latching strip will engage the cap and securely but releasably hold the breech closed. Within the cap or breech there has been provided a cup-shaped plunger 29 which is slidably mounted by 90 means of screws 30 and engaged by a spring 31 which fits about the inwardly extending neck 32 of the plunger. Therefore, this plunger will be normally extended outwardly and when the cap or breech is closed, the plunger will first engage the end of the cartridge and force the cartridge inwardly into the handle 1 as the breech is left shut. The cartridge will thus be forced forwardly 95 into tight engagement with the packing 6 and a tight closure provided about the neck 21 or cartridge outlet between the head 15 and the inner end of the enlarged end 2 of the comb head. This will prevent leakage and all of the ointment forced from the cartridge will be caused to pass into the passage 9.

This breech carries mechanism for turning the threaded stem 16. This mechanism is in the form of a rod or key 33 which is 110 rotatably mounted in the neck 34 of the cap and at its outer end is slotted to receive a turning head 35. The inner end portion is slotted to provide a seat 36 for receiving the arms 19 of the threaded stem 16 thus 115 causing the stem to be rotated with the key 33. A ratchet disk 37 is placed in the cap against the outer end thereof and about the key 33 and is provided with sockets 38 to receive the teeth 39 of the disk 40 mounted 120 upon the key. This disk 40 which constitutes a pawl element is movable longitudinally of the key and is provided with inwardly extending pins or fingers 41 for fitting into the longitudinally extending 125 grooves 42 of the key. The key carries a spring 43 which at one end engages the disk 40 and at its opposite end engages an abutment pin 44 extending through the key. This spring will therefore serve to normally 130

move the key inwardly for engagement with the head 19 of the stem 16 and will further serve to hold the pawl element in engagement with the ratchet element or disk 37.

5 When this device is in use, a cartridge will be placed in the tubular handle and the breech will then be snapped shut. In doing so, the plunger 29 will engage the cartridge to force it tightly into place and the key will 10 engage the arm 19 of the threaded stem. If the key is not turned to just the proper position to permit the arm to move into the slot 36, the spring 43 through engagement with the pin 44 will hold the end of the key in 15 tight engagement with the arm 19 and upon rotation of this key by means of the turning head 35, the slot will be brought into the proper position and the spring will move the key inwardly into operative engagement 20 with the arm of the stem. Continued rotation of the key will rotate the stem 16 and the piston 20 will be moved longitudinally of the stem in the body of the cartridge. This will force the ointment in the cartridge 25 through the cartridge opening or neck 21 and thus into the passage 9 from which it will pass through the passages 11 of the teeth. The spring teeth of the pawl element carried by the key 33 will snap into the 30 sockets 38 of the ratchet disk or plate 37 and the clicking noise produced will indicate the amount of turning which has been given the key and threaded stem. Experience will soon indicate the number of turns which 35 should be given to force the proper amount of ointment out of the cartridge and this will prevent wasting of the ointment. The pawl will further serve its ordinary purpose of preventing the key from being turned in 40 the wrong direction. If desired, the head of the comb may be heated to melt the ointment and cause it to flow freely through the passages of the teeth of the comb but the handle will not be heated from the head as 45 this handle is insulated by the heat resisting bushing 4. When the cartridge is empty, the breech will be opened and since the end of the cartridge extends slightly beyond the end of the hollow handle, it can be easily 50 removed and a new one put in place. The cartridge is not intended to be refilled but will be thrown away when emptied. With the cartridge removed, the comb may be used as an ordinary comb. By removing the 55 plug 10, hot water, steam or any other desired cleaning fluid may be passed through the passages of the head and handle and thus the comb thoroughly cleaned.

60 A modified form of breech construction has been shown in Figs. 12 through 15. In this form, the breech is provided with a cap 45 which will be hingedly connected with the tubular handle and provided with a notch 46 in one side for receiving the hooked end por-

tion of the spring strip 25 to releasably hold 65 the breech in the closed position. Instead of providing a plunger 29, there has been provided a bridge 47 having a central opening 48 through which the arms of the threaded stem 16 will pass. This bridge 70 which is formed of resilient material is provided with side arm 49 which extend inwardly of the cap. The arm 50 is secured to the side of the cap by rivets 51 so that it will be secured to the side of the cap but the arms 75 49 and 50 is provided with a slot 52 through which passes a pin 53 thus slidably mounting the arm 49 and limiting its sliding movement. It will thus be seen that when the cap or breech is closed, the bridge will engage the 80 end of the cartridge and the resiliency of the bridge will force the cartridge tightly into place after the manner in which the spring actuated plunger 29 holds the cartridge in place. The key 54 slidably passes into the 85 cap and is provided at its outer end with a turning head 55 and at its inner end with a notch 56 to receive the arm of the stem. A ratchet wheel 57 is mounted upon this key and fits within a cup 58 where it will be engaged by a pawl 59 carried by the cap. The spring 60 is placed about the key between the ratchet wheel 57 and abutment pin 61 and will serve to normally move the key into position for operatively engaging the arms 19.95 of the threaded stem 16 but at the same time permits outward movement of this key through the ratchet wheel and end of the cap, after the manner in which the spring 43 permits the key 33 to move. It will thus be 100 seen that in this form, the operation will be similar to that disclosed in Fig. 4 but that the details of construction are somewhat different. There has thus been provided a fountain comb which is easy to operate and 105 assemble and not liable to be easily broken or get out of order.

Although attempt has been made to describe the device in exact detail, it is desired that protection be not limited except 110 as set forth in the claims to the exactness illustrated or described, but that such deviation be permitted from the drawings and specification as may be necessary or advisable to facilitate manufacturing, assembling, 115 ease and comfort in operating, or durability, so long as the principal ideas indicated are not unduly departed from.

I claim:

1. A fountain comb comprising a hollow 120 handle and a head having a passage communicating with the handle, a removable dispensing cartridge in the handle including externally operated dispensing means, and a breech comprising a cap for closing the rear 125 end of said handle, actuating means for the dispensing means movably carried by said cap and yieldably held in position for en-

gaging the dispensing means when the breech is closed, and means carried by the cap for yieldably engaging the cartridge and forcing the cartridge tightly into the handle 5 when the breech is closed.

2. A fountain comb comprising a hollow handle and a head having a passage communicating with the handle, a removable dispensing cartridge in the handle including 10 externally operated dispensing means, and a breech for closing the rear end of the handle including movable mounted actuating means for the dispensing means yieldably held in position for engaging the operating means 15 and yieldable means for engaging the cartridge and forcing the cartridge tightly into the handle when the breech is closed.

3. The structure of claim 2 and ratchet means for controlling the direction of rotation of the actuating means carried by the breech, and serving as signaling means.

4. A fountain comb comprising a hollow handle and a head having a passage communicating with the interior of the handle, 25 a dispensing cartridge in the handle including dispensing means having a threaded stem having a turning head, and a breech comprising a cap for closing said hollow handle, a turning key slidably and rotatably 30 carried by the cap and extending externally thereof and having its inner end engageable with the turning head of said stem, resilient means yieldably holding the key in position for operatively engaging the head of the 35 stem, and yieldable means in the cap for engaging the cartridge and forcing the cartridge tightly into the hollow handle when the cap is in a closed position.

5. The structure of claim 4 having a piston 40 ton in the cartridge in threaded engagement with the stem and the stem terminating short of the outlet end of the cartridge whereby the piston may move out of threaded engagement with the stem.

45 6. A fountain comb comprising a hollow handle for receiving a dispensing carriage, a head having an enlarged inner end portion fitting into the forward end portion of the hollow handle, a bushing of heat insulating 50 material positioned in the hollow handle about the portion of the head fitting therein and having its outer end portion extended to provide a circumferentially extending shield, a packing in the handle fitting 55 against the inner end of the head, a breech for the rear end of the handle, means carried by the breech for forcing the cartridge into tight engagement with the packing at the inner end of the head, and actuating means 60 for operating expelling means of a cartridge placed in the handle.

65 7. A fountain comb comprising a tubular handle, a head having a longitudinally extending passage communicating with the interior of the handle, a removable closure

for the outer end of the passage formed in the head, a dispensing cartridge within the handle including dispensing means operated from its outer end, a packing in the handle between the cartridge and the inner end of 70 the head, and a breech for closing the rear end of the tubular handle including means for forcing the cartridge inwardly into tight engagement with the packing to provide a tight joint between the cartridge and inner 75 end of the head, and means carried by the breech for actuating the dispensing means of the cartridge when the breech is closed.

8. A fountain comb including a hollow handle for receiving a dispensing cartridge 80 including dispensing means, and a breech for closing the rear end of the handle, said breech comprising a hollow body, a key extending into the body and provided with a turning element at its outer end and 85 having its inner end adapted for engagement with the dispensing means of a cartridge, a ratchet element in the body about the key and held against rotation, a pawl mounted upon the key and movable longitudinally 90 thereof, a spring positioned upon the key and having one end engaging said pawl and its second end engaging an abutment of the key to hold the pawl in engagement with the ratchet element and the key normally 95 extended for operative engagement with the dispensing means of a cartridge.

9. The structure of claim 8 having the key provided with longitudinally extending grooves and the pawl in the form of a disk 100 slidably mounted upon the key and having tongues extending into the grooves, the disk being formed of resilient material and having tongues for engaging the ratchet.

10. A fountain comb including a hollow 105 handle having a head at one end provided with a passage communicating with the handle, a breech for closing the rear end of the handle, means carried by the breech for actuating dispensing means of a dispensing cartridge positioned in the hollow handle, and means carried by the breech for forcing a cartridge tightly into the hollow handle when the breech is closed, the last mentioned means comprising a cup slidably 110 mounted in the breech and provided with an inwardly extending collar positioned about the actuating means for dispensing means of a cartridge, and a spring fitting about the collar and tending to move the cup outwardly into yielding engagement with a cartridge.

11. A fountain comb comprising a hollow handle of a non-circular shape in cross-section and a head having a passage communicating with the handle, a removable dispensing cartridge in the handle having a tubular body conforming to the shape of the hollow handle in cross section, whereby the cartridge will be held against rotation in the 115 120 125 130

handle, a piston slidably mounted in the tubular body and held against rotation in the tubular body, a threaded stem carrying the piston and journaled in the end of the tubular body and having a turning head at its outer end, and a breech for closing the rear end of the handle including a turning element for engaging the turning head of the

stem when the breech is closed, and means for engaging the cartridge and forcing the cartridge tightly into the handle when the breech is closed.

In testimony whereof I have hereunto set my hand.

ABE R. SPIELBERGER.
